COMBINED REFRIGERATOR AND ICE CREAM FREEZER

Filed Sept. 27, 1929

UNITED STATES PATENT OFFICE

ALBERT F. SAWYER, OF HAVERHILL, MASSACHUSETTS, ASSIGNOR TO IRVING L. KEITH,
OF HAVERHILL, MASSACHUSETTS

COMBINED REFRIGERATOR AND ICE-CREAM FREEZER

Application filed September 27, 1929. Serial No. 395,560.

This invention relates to certain improvements on the combined refrigerating tank and ice cream freezer shown in my pending application Serial Number 316,084, filed October 30, 1928.

The construction shown in said application is open to certain objections, particularly in that the ordinary cooling tank containing non-freezing liquid, usually called the brine tank, is usually located in the top portion of the ordinary domestic refrigerator and is usually accessible through a front door only, necessitating the location of the freezer container in a horizontal position, in which position it is not only difficult to fill the container with the liquid to be frozen, but also the removal thereof is attended with some difficulty. It is also frequently inconvenient to operate the stirring device in the position in which the container is necessarily held, and it is necessary to have the door of the refrigerator open while turning the stirring device.

The objects of the present invention are to obviate the difficulties or objections above referred to, and, at the same time, to provide a means which will enable the usual inconvenience to be avoided which are incident to freezing ice cream by means of mixed ice and salt, and to enable the operation to be performed much more rapidly than with the usual methods.

I accomplish the objects by the means and in the manner hereinafter described and illustrated in the accompanying drawings, in which:

Fig. 1 is a sectional view of an ordinary refrigerator brine tank embodying my invention.

Fig. 2 is a sectional view at line 2--2 of Fig. 1.

Fig. 3 is a detail view, in side elevation partly broken away, of the freezing unit.

In the drawing a brine tank 1, which may be of any suitable form, is illustrated, which will be filled with a liquid which does not freeze at the temperature to which it is likely to be lowered.

According to my invention said tank is provided with a cylindrical recess which

opens to the front side wall of the tank and is formed by a metal, cylindrical wall 3 which extends horizontally therein and is closed at its inner end, the outer end or the rim thereof being soldered, or otherwise permanently connected to the side of the tank about said opening, so as to form a liquid tight connection therewith. The temperature in the brine tank may be maintained at any point which is considered necessary, by any suitable means, preferably by an expansion coil arrangement similar to that disclosed in my said application, and comprising a primary coil 4, which is arranged about the wall 3 in close contact therewith, and a main coil 5 which is connected to the coil 4, in series, so that when the refrigerant passes through the expansion valve 6, it first flows through the coil 4, and then through the coil 5 before it passes to the exhaust side of the circuit. The temperature of the coil 4 about the wall 3 will thus be somewhat lower than the temperature in other portions of the tank.

I further provide a cylindrical metal receptacle 7 having a bottom 8, and a top 9, said receptacle being adapted to be fitted somewhat loosely into the recess enclosed by wall 3. The top 9 is provided with a central circular opening into which a metal cylindrical container 10 is fitted, a permanent liquid tight joint being provided between said top and the side of the container, and a series of radially disposed metal ribs 11 are provided between the outer surface of the container 10 and the inner surface of the receptacle 7, which extend for approximately the length of the container and have a soldered joint connection with one of said surfaces and engage the other.

A series of similar ribs 12 are also provided between the bottom of the container and the bottom 8 of the receptacle, the edges of said ribs being permanently connected to one or the other thereof. A liquid tight jacket is thus provided entirely about the sides and inner end of the container, a filling opening therefor being provided in the top 9 which is closed by means of a plug 13. A closure 14 is provided on the outer end of the container and a rotary stirrer 15 having a crank 16 is

provided in the container, as in the ordinary ice cream freezer.

The chamber between the receptacle and container will be filled with a liquid having a low freezing point, preferably slightly above zero F. in ordinary practice, and the receptacle will be inserted in the recess of the tank, as indicated in Fig. 1. As a result, the temperature of the liquid in the receptacle will be reduced approximately to the temperature of the coil about the wall 3, and the relative freezing point of the liquid and the temperature to which it will be reduced will, preferably, be such that the liquid will become semi-frozen, or changed to "slush ice," with which condition the most satisfactory results, for the purpose, will be secured.

When cream, or other liquid is to be frozen, the receptacle will be removed from the recess in the tank and placed on its bottom, as in Fig. 3, and then the container will be filled and the stirrer will be turned until the contents have been sufficiently frozen, the action of the semi-frozen liquid in the receptacle, which at the beginning of the operation will ordinarily be approximately zero F., being the same as if the receptacle contained a mixture of ice and salt, except that the freezing action will be much more rapid than with ice and salt, as, with the latter, the freezing temperature is usually not secured until a strong brine has been formed, while the inconvenience of preparing this mixture is entirely obviated.

When the contents of the container has been frozen sufficiently, the receptacle and container will be reinserted in the recess of the brine tank, where the freezing operation may be continued, and the frozen condition of the contents may be maintained indefinitely.

The freezing operation may be performed while the removable parts are inserted in the recess of the tank, and, while this operation might thus be performed somewhat more quickly, it will usually be much more convenient to operate the stirring device while the parts are removed. However, by having the container surrounded with ice, or semi-fluid ice at a temperature much lower than the freezing point of water the rapidity with which the freezing operation will be performed will be greatly facilitated, as compared with the results which would be secured if the container were directly fitted to the recess in the tank.

I claim:

1. A freezing device of the character described comprising a container having a closure at its top and a stirring device therefor, a receptacle within which said container is supported, the sides of said receptacle being connected to the sides of the container adjacent the closure thereof, to provide a liquid tight chamber about the container, said chamber having a liquid therein, the freezing

point of which approximately corresponds to the freezing temperature required in the container, and a refrigerating device having a recess adapted to receive said receptacle and to reduce the temperature of the liquid in said chamber to the desired point. 70

2. A freezing device of the character described comprising a container having a stirring device and a closure for the top end thereof, a receptacle entirely enclosing said container, except at the top thereof, the sides of the receptacle being connected to the sides of the container at the top ends thereof and providing a liquid tight chamber about the sides and bottom of the container, said chamber having a low point freezing liquid therein and a refrigerating device having a recess adapted to receive said receptacle and reduce the temperature of the liquid therein to the temperature required to freeze the 85 contents of the container. 75

3. A freezing device of the character described comprising a container having a stirring device and a closure for the top end thereof, a receptacle entirely enclosing said container, except at the top thereof, the sides of the receptacle being connected to the sides of the container at the top ends thereof and providing a liquid tight chamber about the sides and bottom of the container, said chamber having a low point freezing liquid thereon, a series of heat conducting fins extending between the sides of the container and the sides of the receptacle within said chamber, and a refrigerating tank having a recess therein opening to one side thereof and into which said receptacle is adapted to be loosely fitted to reduce the temperature of the liquid in the receptacle to the temperature required to freeze the contents of the container. 95 100

In testimony whereof, I have signed my name to this specification.

ALBERT F. SAWYER.
